Term of patent 14 years

(Cl. D4—26)

FIG. 1

FIG. 2

FIG. 3

FIGURE 1 is a top plan view of a portable manually operated scraper blade showing my new design.

FIGURE 2 is a section view along line 2—2 of FIGURE 1.

FIGURE 3 is a perspective view thereof.

The dominant features of my design reside in the portions shown in full lines, the broken line showing of the handle being for illustrative purposes only.

I claim:

The ornamental design for a portable manually operated scraper blade, as shown and described.
